(57) **CLAIM**

The ornamental design for a sink, as shown and described.

DESCRIPTION

FIG. 1 is a top, front, and left side perspective view of a sink in accordance with a first embodiment of the design; FIG. 2 is a bottom, front, and left side perspective view of a sink of FIG. 1; FIG. 3 is a top plan view of the sink of FIG. 1;

FIG. 4 is a front elevational view of the sink of FIG. 1;

FIG. 5 is a left side elevational view of the sink of FIG. 1;

FIG. 6 is a right side elevational view of the sink of FIG. 1;

FIG. 7 is a rear elevational view of the sink of FIG. 1;

FIG. 8 is a bottom plan view of the sink of FIG. 1;

FIG. 9 is a cross-sectional side view of the sink of FIG. 1 taken through line 9-9 of FIG. 3;

FIG. 10 is a top, front, and left side perspective view of a sink in accordance with a second embodiment of the design, which has two basins.

FIG. 11 is a bottom, front, and left side perspective view of the sink of FIG. 10;

FIG. 12 is a top plan view of the sink of FIG. 10;

FIG. 13 is a front elevational view of the sink of FIG. 10;

FIG. 14 is a left side elevational view of the sink of FIG. 10;

FIG. 15 is a right side elevational view of the sink of FIG. 10;

FIG. 16 is a rear elevational view of the sink of FIG. 10; FIG. 17 is a bottom plan view of the sink of FIG. 10; and, FIG. 18 is a cross-sectional side view of the sink of FIG. 10 taken through line 18-18 of FIG. 12.

The broken lines illustrate unclaimed subject matter only and form no part of the claimed design.

The sink is shown with a symbolic break in its length. The appearance of any portion of the article between the break lines forms no part of the claimed design.

1 Claim, 11 Drawing Sheets
